United States Patent Office.

JOHN W. WALTERS, OF RICEVILLE, IOWA.

Letters Patent No. 77,137, dated April 21, 1868.

IMPROVEMENT IN MACHINES FOR BORING HUBS.

The Schedule referred to in these Letters Patent and making part of the same.

TO ALL WHOM IT MAY CONCERN:

Be it known that I, JOHN W. WALTERS, of Riceville, in the county of Mitchell, and State of Iowa, have invented a new and improved Reaming-Machine; and I do hereby declare that the following is a full, clear, and exact description thereof, which will enable those skilled in the art to make and use the same, reference being had to the accompanying drawings, forming part of this specification.

This invention relates to an improved reaming-machine. It consists of a cutting-tool, having a thread on its shank, setting into a box in which is a vertical-toothed or mitre-wheel, having an inside thread, corresponding with that on the shank of the cutting-tool.

A crown or mitre-gear, solidly secured to the bottom of a hollow shaft or sleeve, surmounted by a hand-wheel, operates the inside-threaded gear-wheel, for the purpose of adjusting the cutting-tool as desired. A rod, securely attached to the bottom of the box in which the cutting-tool is carried, screws into a clamp, while the upper clamp slides loosely on the hollow shaft or sleeve, and another rod securely attached to top of said box, passes through said sleeve, and is operated by a handle, connected to and released from the hand-wheel, by a suitable device, as desired. In the accompanying drawings—

Figure 1 is a vertical section of my improved reamer, and

Figure 2 is a view, on a larger scale, of the crown-gear and its attachments.

Similar letters of reference indicate corresponding parts.

A is a threaded shaft, solidly attached to the metal box B. C is the lower clamp, which is most conveniently made three-armed, having a female thread, into which the shaft A works, and clamping the hub D by the set-screws c c'.

The cutting-tool E fits into the metal box B, and its shank is provided with a thread, e, upon which works the vertical-toothed wheel F, or an equivalent gear-wheel, within the box B.

G, in the present instance, is a crown-gear wheel, which engages with the toothed wheel F, and carries the hollow shaft or sleeve H, surmounted by the hand-wheel L.

The shaft K, having attached to it, at the top, the handle L, is solidly secured to the top of the box B, and passes through the sleeve H, so that the threaded shaft A, box B, and shaft K, always operate together as one piece.

The upper clamp, C', slides loosely on the hollow shaft H, and is clamped to the hub by set-screws c' c'.

The hand-wheel I is provided with holes in its rim, into which sets the pin l, to hold the handle L and its attachments to the hand-wheel I, and its attachments, when desired; and the cutting-tool being adjusted, as presently mentioned, and the reamer attached and clamped to the hub, by turning the handle L, the reamer is operated, and the threaded shaft A screwed into the lower clamp C, the shaft H at the same time descending through the loose upper clamp C'.

The pin l, which is attached to the under side of the spring M, passes through the handle L, and hand-wheel I, and a bent lever, N, having its fulcrum in said handle L, at n, raises the pin l out of the hand-wheel, enabling the hand-wheel and its attachments to be turned for the purpose of adjusting the cutting-tool, while the handle L and its attachments remain stationary, thus operating the toothed wheel F upon the thread of the shank e, of the cutting-tool E, and projecting or retiring said cutting-tool, as desired.

The threaded shaft A should equal or slightly exceed in length the distance from the bottom of the box B to the hand-wheel I.

I claim as new, and desire to secure by Letters Patent—

The combination of the two shafts A K, the latter having the crown-gear wheel G, tubular shaft H, box B, adjustable cutter E, having the pinion F, all operating as described for the purpose specified.

JOHN W. WALTERS.
